UNITED STATES PATENT OFFICE.

EDWARD G. SCHATTE, OF AUBURN, NEW YORK.

CLUSTER LAMP-SOCKET.

1,385,844.

Specification of Letters Patent. Patented July 26, 1921.

Application filed July 29, 1919. Serial No. 314,094.

To all whom it may concern:

Be it known that I, EDWARD G. SCHATTE, a citizen of the United States of America, and resident of the city of Auburn, State of New York, United States of America, have invented certain new and useful Improvements in Cluster Lamp-Sockets, described in the following specification and illustrated in the accompanying drawings, that form part of the same.

The principal objects of this invention are to simplify the construction of lamp sockets of the cluster type so as to minimize the cost of construction and to produce a compact and rigid device which will be very easy to assemble and will maintain secure electrical contacts.

The principal feature of the invention consists in the novel construction of a molded composition body and of the several electrical connections whereby the molding of the composition body is accomplished with the simplest form of mold and the assembling is greatly facilitated.

In the drawings, Figure 1 is a mid-sectional elevational view through the double socket structure.

Fig. 2 is a central transverse longitudinal section.

Fig. 3 is a perspective view of the molded member showing the plug member assembled and ready for insertion.

The body member 1 is formed of a suitable molding composition such as bakelite and is a unitary structure formed with the acute angularly disposed socket portions 2 and a recess 3 extending downwardly from the top. Holes 4 connect the recess 3 with the interior of the socket portions 2 at the inward side.

A member 5 formed of brass plate and cut in a substantially inverted V-shape is preferably molded into the bakelite, though it may be assembled into the molded member if desired. This member is formed with a right angularly bent lug 6 at the apex and lugs 7 at the extremities. Each of these lugs have threaded holes through the center. If the member 5 is molded into the bakelite it is supported in the mold by pins secured in the mold and extending into the holes in the lugs which are centrally located in relation to the top and socket portions of the body.

The plug shell 8 has secured to its inner side at the bottom end a flat metal strip 9,

the free end of which is formed with a pair of right angularly bent lugs 10, which are arranged at an obtuse angle in relation to each other and are formed with threaded holes, which when the member is inserted in place, register centrally with the holes 4 in the bakelite body.

The plug center is herein shown formed of two cylindrical-shaped blocks 11 and 12. The outer block 11 engages the flange of the plug shell 8 and extends above the same in the ordinary manner. The block 12 is formed with a flange 13 which abuts the top of the body and engages the bottom edge of the plug shell. The block 12 is formed with a recess 12' through which the member 9 is inserted and the lug end thereof extends into the recess 3 and is shaped so as to pass the lugs 6 of the member 5. The center plug contact screw 14 passes through the plug members and is secured in the threaded hole in the lug 6.

The socket shells 15 are inserted into the socket portions 2 and screws 16 are inserted through holes in the inner end flanges of the shells 15 and engage the threaded holes in the lugs 10 of the plug strip 9.

Insulating washers 18 are then inserted in the shells to cover the screws 16 and these are held in place by the screws 19 which extend through the holes 20 in the bakelite and are threaded into the lug ends 7 of the member 5.

It will be seen from this description that the various parts are of the very simplest construction and they can be assembled very rapidly. The use of the double plug block is not essential though important as it renders it very easy of assembly and gives an extra length to the plug portion which will fit any socket.

What I claim as my invention is:

1. A cluster lamp socket, comprising, a unitary molded body portion formed with a plurality of socket openings connecting at the inner ends with a recess opening through the top, a unitary metal member arranged in said recess having branch arms extending to each of said sockets, a threaded plug shell having a connection member rigidly secured thereto and extending into the recess in said body, socket shells arranged in said socket recesses and rigidly connected to the member secured to said plug shell, a plug arranged in said plug shell recessed to receive the plug shell connection, an electrical con-

- nection extending centrally through said plug and secured to the unitary metal member, and central socket contacts secured in the extremities of the arms of the unitary member. 20
2. A cluster lamp socket, comprising, a unitary molded body having a plurality of socket recesses and a central recess opening from the top and communicating with said recesses, a V-shaped metal member having laterally turned lugs at the apex and at the ends, said lugs having threaded holes, said member being molded rigidly in said molded body with the holes centralized in relation to the recesses, a plug shell having a flat metal strip rigidly secured to its interior and projecting therefrom and having a pair of lugs at the free end formed with threaded holes, said member being adapted to extend into the recess in the body, plug blocks supporting said shell, a central contact screw extending through said plug blocks and secured to the top lug of the V member, central contacts connected to the end lugs of the V member, socket shells arranged in the 25 socket recesses, and screws connecting the socket shells with the end lugs of the plug shell extension. 25

EDWARD G. SCHATTLE.
